(57) **CLAIM**

The ornamental design for a seat belt connector for motor vehicles, as shown and described.

DESCRIPTION

FIG. 1 is a front perspective view of a seat belt connector for motor vehicles;

FIG. 2 is a rear perspective view thereof;

FIG. 3 is an elevation view thereof from the right side;

FIG. 4 is an elevation view thereof from the left side;

FIG. 5 is a rear perspective view thereof;

FIG. 6 is a front perspective view thereof;

FIG. 7 is a top plan view thereof; and,

FIG. 8 is a bottom plan view thereof.

1 Claim, 4 Drawing Sheets
